UNITED STATES PATENT OFFICE.

JULES A. FREMON, OF LEEPER, MISSOURI.

MASTER-KEYED LOCK.

Application filed November 10, 1921. Serial No. 514,245.

To all whom it may concern:

Be it known that I, JULES A. FREMON, a citizen of the United States, residing at Leeper, Missouri, have invented a certain 5 new and useful Improvement in Master-Keyed Locks, of which the following is a full, clear, and exact description, such as will enable others skilled in the art to which it appertains to make and use the same, 10 reference being had to the accompanying drawings, forming part of this application.

My invention relates to pin tumbler locks of the type described in my copending application Serial Number 510,830, and consists in various improvements on the lock 15 there shown which especially adapt it for use as a master keyed lock or as a multiple key lock and which produces a more durable and easier working lock whether used as a 20 single key, master key, or multiple key lock.

One of the objects of my invention is to so lock the separable members containing the pin tumblers to each other that the pin tumbler recesses will be rigidly aligned, 25 thereby avoiding catching of the ends of the pin tumblers upon the edges of the lock members and undue wear of the pin tumblers.

Another object of my invention is to provide a master keyed lock that affords the same degree of protection against the use of unauthorized keys as is afforded by a straight pin tumbler lock.

Another object of my invention is to provide means for master keying a lock to any desired extent, that is, in addition to the service key and the master key, the lock may be adapted for sub-master keys, grand master keys, etc.

40 An additional object of my invention is to provide means for enabling the possessor of a service key to change same at will without affecting the operation of the master keys and similarly to enable the possessor 45 of any master key to change same without affecting the possessor of the service key or any other master key.

In the accompanying drawings, which illustrate my invention—

50 Figure 1 is a vertical longitudinal section through my improved pin tumbler lock adapted for changeable key construction.

Figures 2 to 6 inclusive, are vertical trans-

verse sections, largely diagrammatic, taken approximately on the line 2—2 of Figure 1, 55 but showing the various parts in different operating positions.

Figure 7 is an enlarged section similar to Figure 2 and illustrating certain details omitted from Figures 2 to 6 inclusive to 60 avoid confusion in the latter.

Figure 8 is a longitudinal section on line 8—8 of Figure 7.

Figures 9, 10 and 11 illustrate a modified 65 form of my invention.

Figure 12 illustrates another modification which embodies my invention in one of its simplest forms.

To more clearly describe my lock and its operation, I shall first explain the simpler 70 construction illustrated in Figure 12, although the same does not contain the changeable key feature referred to above and, therefore, in some respects is more limited in its capacity.

The lock case 1 is cylindrical in form and provided with upper and lower extensions 2 and 3, respectively. Rotatably mounted in case 1 are successive rings 4, 5 and 6 and a cylindrical plug 7. The case, rings and 80 plug may be arranged eccentrically as here shown, or concentrically as shown in Figures 1 to 8. Plug 7 contains an axial key-way 8 for receiving and holding a key against vertical movement in the usual manner. An 85 ordinary bolt-throwing-cam (not shown) is mounted on the rear end of the plug. The case, each of the rings, and the plug contain a pin-way for the reception of respective pin tumbler segments 9, 10, 11, 12 and 90 13. All of these pin-ways are adapted to be aligned as shown in Figure 12 to permit raising of the pins by the key bits to register the meeting ends of any two predetermined segments with the meeting surfaces of their 95 two corresponding rings or case and ring 4 or plug and ring 6.

The case, rings and plug are provided with another series of pin-ways extending downwardly, offset from the pin tumbler 100 pin-ways longitudinally of case 1, and adapted to receive aligning pins 14 and 15. Preferably the fit between pins 14 and 15 and the pin-way for these pins is substantially closer than that between pin tumblers 105 9 to 13 and their pin-ways. Consequently

pin tumblers 9 to 13 will be free to move up and down independently of any friction with the sides of the passageway through the case, rings and plug which otherwise might 5 be caused by undesired rotation of the rings relatively to each other or the case and plug.

The lengths of pin tumblers 9 to 13 are such that when a key is inserted in plug 7, there will be a single registration of the ends 10 of two pin tumblers with the meeting surfaces of two of the containing members.

A grand master key will be adapted to rotate plug 7 only by raising the top of segment 13 to the top of the plug and lowering 15 the bottom of aligning pin 14 to the bottom of plug 7. This will leave all of the rings locked to the case and each other by segments 9 to 12 and incidentally by aligning pin 15. Upon insertion of a master key, the 20 top of segment 12 will be raised to the top of ring 6 and the bottom of pin 14 will be lowered to the bottom of ring 6, but segment 13 will lock ring 6 to plug 7 and incidentally pin 14 will similarly lock the plug 25 and adjacent ring. Plug 7 and ring 6 may be rotated as a unit by this key to throw the lock bolt. Upon insertion of a sub-master key, the top of segment 11 will be raised to the top of ring 5 and the bottom of pin 14 30 lowered to the bottom of ring 5. Segments 12 and 13 will lock rings 5 and 6 to each other and to plug 7 and incidentally pin 14 will lock plug 7 and rings 5 and 6 together. The plug and the two adjacent rings will be 35 rotated as a unit to throw the bolt. Upon insertion of a service key, all of the rings and plug will be similarly locked and rotatable as a unit in case 1.

In all of these operations, the close fit of 40 pins 14 and 15 in their pin-ways will maintain an accurate alignment of the tubular pin-ways to permit free and easy movement of the pin tumblers as actuated by the key bits or springs 16. It will be understood 45 that there is a longitudinal series of radial pin tumbler pin-ways but that only one aligning pin recess is necessary, although more may be used, if desired. If only one set of aligning pins is provided, the single 50 aligning pin bit on each of the keys may be so positioned that a long gradual incline to the crest of the bit may be used, thereby permitting the insertion of a spring 17 of 55 heavier compression than ordinarily used to operate the pin tumblers in locks. This will overcome any friction resulting from the closer fit between pins 14 and 15 and their recess wall.

Theoretically, there is no limit to the 60 number of successive rings which may be provided in a lock of this type, and each ring in the lock provides means for the use of another master key. Thus in a hotel installation, the guest would have a service key, a floor clerk could have a key for all

the locks on one floor only, another employee could have a key for all of the locks on several floors or one wing of the building, and a manager could have a key for all of the locks in the building and so on.

Now referring to the preferred embodiment of my invention illustrated in Figures 1 to 8, inclusive, the basic principle of operation of the lock is the same as in the construction shown in Figure 12, but the addition of the changeable key feature as disclosed in my above-mentioned application makes the lock somewhat more complicated and adds a number of details which will now be described.

The lock illustrated is constructed for service key and master key only, but either of these keys may be changed when desired.

The case 18 is here shown with a single upward extension 19 and rings 20, 21 and 22 are disposed concentrically within the case and about plug 23. The key slot is located in the center of the plug instead of in the lower portion. In addition to service key pin tumblers 24, 25, 26, 27, and 28 and master key pin tumblers 29, 30, and 31, the lock contains uniting pins 33 and 34 located respectively in rings 20 and 22. Pin 33 is adapted to be projected inwardly as shown in Figure 2 to unite ring 20 with ring 21, or to be projected outwardly as shown in Figure 4 to lock ring 20 to case 18 temporarily. Pin 34 is adapted to be projected inwardly as shown in Figure 2 to unite ring 22 with plug 23, or to be projected outwardly as shown in Figure 6 to lock ring 22 to ring 21 temporarily. Each of these uniting pins is provided with a spring 35 which tends to thrust the pin outwardly.

Case 18 and ring 21 are provided with sliding bars 36 and 37, respectively, which normally provide the inner face of case 18 and ring 21 with continuous surfaces over which the heads of pins 33 and 34 may slide. Bar 36 in case 18 is normally projected rearwardly therefrom by a spring 38. Finger pressure upon the projecting end of bar 36 will force same forwardly so as to align a recess 39 in the bar with the path of movement of pin 33. Bar 37, which is slidably mounted in ring 21, normally terminates adjacent to the end of the ring and inside of case 18 so as not to interfere with rotation of the ring in the case. A short supplementary pin 45 is slidably mounted in case 18 and normally projects to the rear thereof, as indicated by dotted lines in Figure 8 to afford means for manually pushing bar 37 to the front to permit operation of pin 34 similarly to the above described operation of pin 33.

The normal locked position of the various units is shown in Figures 2 and 7. When there is no key in the plug key slot, the case 18, rings 20, 21 and 22 and plug 23 are all

locked against relative rotation by pin tumblers 24, 25, 26, 27 and 28. Rings 21 and 22 and plug 23 are also locked against rotation by pin tumblers 29, 30 and 31. Rings 20 and 21 are united by uniting pin 33 and ring 22 and plug 23 are united by uniting pin 34.

When the master key is inserted as shown in Figure 3, pin tumblers 24, 25, 26, 27 and 28 are raised so that the meeting ends of tumblers 24 and 25 register with the meeting surfaces of ring 20 and case 18, thus permitting the rotation of rings 20, 21 and 22 and plug 23, as a unit.

When the service key is inserted as shown in Figure 4, pin tumblers 24, 25, 26, 27, and 28 are raised so that the meeting ends of pins 26 and 27 register with the meeting surfaces of rings 21 and 22, and pin tumblers 29, 30 and 31 are lowered so that the meeting ends of pins 30 and 31 also register with the meeting surfaces of rings 21 and 22, thus permitting the rotation of rings 20 and 21 and plug 23 as a unit within ring 22.

It will be understood that the cam *c* affixed to plug 23 will operate the latch bolt in either of the above operations.

To effect a change of master keys, the present master key is inserted, as shown in Figure 3, and bar 36 is pressed forward, as shown in Figure 8, so as to align recess 39 in the bar with the path of movement of uniting pin 33.

Upon rotation of ring 20, pin 33 engages the recess in bar 36 to lock the ring to the case and disengages ring 21 to permit rotation of the parts inside of ring 20 to the position shown in Figure 5. At this point, the pin tumblers 26, 27 and 28 in the plug and rings 21 and 22 are aligned with a pin segment recess in ring 20 containing segments 40 which are thrust inwardly by means of a wire 41 secured to a coil spring 42. Upon withdrawal of the master key, the pin-way in rings 21 and 22 and plug 23 will be filled to the outer periphery of ring 21 with pin tumblers and pin segments and upon the insertion of a master key with a different height of bit aligned with these pin tumblers, a different number of segments 40 will be thrust outwardly into ring 20 and upon rotation of ring 20 to the right, the lock will be changed for the master key only. Upon such rotation, the inclined righthand face of recess 39 will cam pin 33 out of the recess into its original position in which it engages ring 21.

Ordinarily uniting pin 33 prevents relative rotation of rings 20 and 21 but when uniting pin 33 is in recess 39 it does not so function and ring 21 may be rotated a short distance within ring 20. This rotation is limited by the provision of a stud 43 on ring 21 and an arcuate slot 44. When stud 43 is at the lefthand end of slot 44, it will stop the rotation of the key and the op-

erator will know that the lock parts are in master-key-changing position.

During the entire key-changing operation just described, the operation of the service key remains unaffected due to the fact that the master key does not operate pin tumblers 29, 30 and 31.

The above-described operation for the purpose of changing the number of pin tumbler segments for the master key is substantially duplicated for the purpose of changing the pin tumbler segments in ring 22 for the service key, it being understood that by manipulation of bar 37, ring 22 is locked to ring 21 to prevent its rotation, and that the lower pin-way in plug 23 is filled to its outer periphery from the segment reservoir in ring 21. Plug 23 has a stud 49 and ring 22 has a slot 50 which elements correspond to and function as stud 43 and slot 44. The changing of the service key does not affect the master key tumblers, since the insertion of the service key lifts tumblers 24 to 28 to the position shown in Figure 4 to permit rotation of plug 23 and ring 22 but such movement of these tumblers does not result in changing the distance from the bottom end of pin 28 to the top end of pin 25.

It should be noted that the service key must operate both sets of tumblers and all service keys that may be fitted to the lock will have the same bitting on the master key edge but the master key operates only one set of tumblers and therefore is bitted on one edge only.

In the modification shown in Figures 9 to 11, the annular rings are replaced by arcuate annular members 46 and 47 which are locked together and rotated similar to the rings previously described but are limited in their rotation to approximately ninety degrees when the ends of the members will contact with the end of their recess in the case 48. This will provide a cheaper construction and in many installations will be as desirable as the more expensive construction illustrated in the other embodiments of my invention in which the annular members are rings and which may be free to rotate unlimited distance in either direction.

In any of the forms shown, although there are a plurality of relatively movable parts, when the lock is being operated normally by any key, there are but two relatively moving units. In this respect my lock retains the simplicity and advantages of the ordinary simple pin tumbler lock. When it is desired to change one key, the elements not involved in the changing operation are securely enclosed and it is impossible to get any of the pin tumblers or their segments in the wrong recess.

These advantages are common to the

forms illustrated and it is obvious that various other modifications will suggest themselves to those skilled in the art without departure from the spirit of my invention, 5 as expressed in the following claims:

I claim:

1. In a pin tumbler lock, a plug, a plurality of annular members surrounding said plug, a pinway through said members, pin 10 tumblers in said pinway, and tumbler section reservoirs in different ones of said members.
2. In a pin tumbler lock, a plug, a plurality of annular members surrounding said plug, a pinway through said members, pin 15 tumblers in said pinway, tumbler section reservoirs in different ones of said members, and pins for selectively uniting certain of said members with each other to provide 20 access to said reservoirs by different portions of said pinway.
3. In a pin tumbler lock, a case member, a plug, a plurality of annular members surrounding said plug, a pinway through said 25 members, pin tumblers in said pinway, and tumbler section reservoirs in different ones of said members.
4. In a pin tumbler lock, a plug, a plurality of annular members surrounding said plug, a pinway through said members, pin 30 tumblers in said pinway, tumbler section reservoirs in different ones of said members, and key means for transferring pin tumblers from said pinway to any of said reservoirs and vice versa.
5. In a pin tumbler lock, a plug, a plurality of annular members surrounding said plug, a pinway through said members, pin 35 tumblers in said pinway, tumbler section reservoirs in different ones of said members, and key means for transferring pin tumbler sections from different portions of said pinway intermediate its ends to respective ones of said reservoirs and vice versa.
6. In a pin tumbler lock, a plug, a plurality of members surrounding said plug, all of the above-mentioned elements being 40 rotatable relative to each other, pin tumblers, and key controlled means aside from said tumblers for selectively locking each of the above-mentioned elements to its adjacent element or elements.
7. In a pin tumbler lock, a case, a plug member, a plurality of members between 45 said case and plug, all of the above-mentioned members being freely rotatable relatively to each other, pin tumblers, and key controlled means aside from said tumblers for locking each of the above-mentioned elements to its adjacent element or elements.
8. In a pin tumbler lock, a case, a rotatable plug, a bolt cam fixed thereto, a series 50 of annular members enclosing said plug and rotatable thereon, pin tumblers, and other 55 key-controlled pins for selectively locking 60 elements to one or more of said members.

9. In a pin tumbler lock, a case, a rotatable plug, a bolt cam fixed thereto, a series 65 of annular members enclosing said plug and rotatable thereon, pin tumblers, and other 70 key-controlled pins for selectively locking said plug to one or more of said members and for locking the remainder, if any, of said members to said case.

10. In a pin tumbler lock, a case, a rotatable plug, a bolt cam fixed thereto, a series 75 of annular members enclosing said plug and rotatable thereon, pin tumblers, and other 80 key-controlled pins for selectively locking one or more of said members to said case.

11. In a pin tumbler lock, a case, a rotatable plug, successive rotatable annular members surrounding said plug, pin-ways in said 85 members, plug and case, adapted to be aligned to form a continuous tubular pinway, and pin tumblers each corresponding in length to the thickness of the respective member in which it is located and separate means for holding said pinways aligned.

12. In a pin tumbler lock, a case, a rotatable plug, successive rotatable annular members surrounding said plug, pin-ways in said 90 members, plug and case, adapted to be aligned to form a continuous tubular pinway, pin tumblers each corresponding in 95 length to the thickness of the respective member in which it is located, and aligning pins extending through said members, plug and case to insure free operation of said pin tumblers.

13. In a pin tumbler lock, a case, a rotatable plug, successive rotatable annular members surrounding said plug, pin-ways in said 100 members, plug and case, adapted to be aligned to form a continuous tubular pinway, and pin tumblers in said aligned pinways formed in sections which adapt the pin tumbler to be parted between the plug and the adjacent member, between any two adjacent members, or between the case and the 105 adjacent member, and key-controlled pins for aligning said pin-ways independently of the action of said pin tumblers.

14. In a master keyed lock, a case, a plug, an annular member therebetween enclosing 110 said plug, pin-ways extending through said member, case and plug, pins in said pinways adapted to lock the above-mentioned elements to each other and adapted to be parted between different pairs of said elements by different keys to permit operation 115 of the lock.

15. In a master keyed lock, a case, a plug, annular members therebetween, pinways through the above-mentioned elements 120 adapted to be aligned throughout their length, pin tumblers in certain of said pinways to be engaged by a service key only, and pin tumblers in other of said pinways 125 to be engaged by a master key only, said 130

latter mentioned tumblers serving to align all of said first-mentioned tumbler pinways when a service key is inserted in the lock.

16. In a changeable-key pin-tumbler lock, 5 a case, a plug, a pin-way therethrough, a series of locking pin tumbler segments in said pin-way, which adapt the pin tumblers formed thereby to be parted at various points in their lengths to accommodate different 10 bitted keys, and means independent of said pin tumblers for aligning said pin-ways.

17. In a changeable-key pin-tumbler lock, 15 a case, a plug, annular members therebetween, a pin-way through said members, case and plug, a series of pin tumbler segments in said pin-way which adapt the pin tumblers formed thereby to be parted at various points in their lengths to accommodate different bitted keys, and means for 20 aligning said pin-ways comprising other pin-ways and other pins which lock said annular members to said case and plug except at the radial point at which the pin tumblers are to be parted.

25 18. In a pin tumbler lock, a key receiving plug, a member in which said plug is rotat-

able, a plurality of cylindrical pinways in said plug and member, cylindrical pins in said pinways, one of said pins fitting its pinway more closely than the other pins fit 30 their pinways and serving as an aligning member for said plug and member.

19. In a pin tumbler lock, a key receiving plug, a member in which said plug is rotatable, a plurality of pinways for locking pins 35 in one side of said plug and the adjacent portion of said member, a cylindrical pinway in the opposite side of said plug and the adjacent portion of said member a cylindrical 40 aligning pin fitting in said cylindrical pinway more closely than said locking pins fit their pinways.

20. In a master keyed pin tumbler lock, a plug, a member in which said plug is rotatable, and pin tumblers in said plug and 45 member, only some of which pins are operable by a master key and all of which pins are operable by a service key.

In testimony whereof I hereunto affix my signature this 4th day of November, 1921.

JULES A. FREMON.
